UNITED STATES PATENT OFFICE.

JEREMIAH J. LYNCH, OF BROOKLYN, NEW YORK.

GAME.

Application filed December 21, 1923. Serial No. 682,016.

To all whom it may concern:

Be it known that I, JEREMIAH J. LYNCH, a citizen of the United States, and a resident of the city of New York, borough of Brooklyn, in the county of Kings and State of New York, have invented a new and Improved Game, of which the following is a full, clear, and exact description.

The present invention relates to new and useful improvements in games, and it pertains more particularly to the type of games in which the players move around bases and also employ a bat and ball.

It is one of the primary objects of the invention to provide a new and improved game which will furnish exercise and recreation for the participants.

It is a further object of the invention to provide a game requiring skill in its play and which game will develop skill on the part of the players.

It is a further object of the invention to provide a game which may be played either indoors or outdoors with the same game apparatus and in the same manner.

With the above and other objects in view, reference is had to the accompanying drawings, in which

Figure 1 is a top plan view of a playing field laid out in accordance with the requirements of the game illustrated in the present application;

Fig. 2 is a view in front elevation of a portion of the apparatus used;

Fig. 3 is a vertical sectional view taken on the line 3—3 of Fig. 2;

Fig. 4 is a detail horizontal sectional view taken on the line 4—4 of Fig. 2;

Fig. 5 is a detail perspective view of one of the elements used as a base;

Fig. 6 is a detail perspective view of the bat or paddle used in the playing of the game.

Referring more particularly to the drawings, the reference character 10 designates a playing field, and such playing field is bounded on the sides by markers or lines 11 and on the ends by markers or lines 12. At one end of the playing field there is a base 13, and at the other end there is a base 14. On one side of the playing field there are bases 15, 16 and 17, and upon the opposite side of the playing field there are bases 18, 19 and 20.

Mounted intermediate of the ends of the playing field there is a barrier A and the

specific construction of this barrier will be hereinafter described. On the right-hand side of the barrier A, in Fig. 1, there is a bouncing plot B and on the left-hand side of the field in Fig. 1, there is a bouncing plot C. These bouncing plots are each the same distance from the barrier and their function will be hereinafter referred to.

By reference to Figs. 2 to 4, it will be noted that the barrier A comprises two plates 21 and 22 hingedly connected together as at 23. The plate 21 has key-slots 24 therein and such key-slots 24 are adapted to receive screws or the like, 25, carried by standards 26. Each of these plates is provided with a plurality of openings circular in form and designated by the reference numeral 27, the openings in one plate registering with those in the other. Adapted to be retained between the plates, there is a sheet of tissue paper or other fragile material, 28, and the plates are held in closed position with the sheet of fragile material therebetween, by means of clips or the like, 29. The sheet of fragile material 28 is printed with a plurality of Roman characters, designated by the reference character R, and ranging from "I" to "V", which Roman characters are visible through the openings 27 on opposite sides of the barrier when the sheet 28 is placed between the plates 21 and 22.

The standards 26 heretofore mentioned are supported by pivoted legs 30, and such standards are connected to the pivoted legs 30 at their pivotal points 31. The reference numeral 32 designates chains or other stays connected to the lower ends of the standards and to their respective pivoted legs to prevent accidental movement of the standards and pivoted legs about their pivotal points 31. Carried by the upper end of each of the standards there is a flag or the like, 35, and each of such flags is carried by a staff 36 adapted to be received within a recess in the upper end of the standard 26, or otherwise secured thereto.

As shown in Fig. 5 of the drawings, the several bases are circular in form, and the material cut from the plates of the barrier may be used in this connection if desired.

Fig. 6 discloses a paddle or the like which is used in playing the game, and the paddle comprises a head portion 40 from which projects a handle 41, the opposite sides of the handle being faced with reinforcing strips

or the like 42, by which the necessary strength is given to the paddle.

The game is played in the following manner:

5 The contestants are divided into two groups constituting teams and each team occupies one end of the playing field. After it has been decided which team is to start the play, one of the members of that team, for 10 instance, the team on the right in Fig. 1, stands in the bouncing plot B and tosses a missile, such as a soft rubber ball, over the barrier, causing the ball to land in the bouncing plot C. Previous to this, the players of the other team have taken their position around the bouncing plot C, and as the ball bounds one of them hits it with the bat or paddle and drives the ball at the barrier. If the ball passes through one of the 15 openings and ruptures the fragile material 28, the player of the team for which the shot was made, advances a number of bases corresponding to the value of the opening through which the ball passed. If, however, 20 the ball hits the barrier without rupturing the fragile material and rebounds therefrom, there is no score or progress. After the fragile material has been broken through 25 each of the openings in any desired number of barriers, for example, ten, the game is then at an end, the winning side being the one scoring the larger number of points or bases. When a barrier has been completely 30 used up, the members of the barrier are opened and a new sheet of fragile material is placed therein and the game proceeds until the fragile material covering the several 35 openings is again broken.

The foregoing is the fundamental principle 40 of the game, and, of course, modifications in the rules of play may be resorted to without departing from the spirit of the invention. Furthermore, if desired, in lieu of printing with Roman characters upon the 45 fragile material to be ruptured, the several openings in the plates of the barrier may be numbered on the plates rather than on the fragile material without departing from the invention.

50 From the foregoing it is apparent that the present invention provides a new and improved game which may be played either indoors or outdoors, and in which physical exercise and considerable skill result in the 55 playing thereof.

What is claimed is:

1. A game apparatus including a playing field, a plurality of bases bordering said playing field and forming stations and a 60 barrier having a plurality of openings of different values and through which a missile is to be projected to determine the number of bases a player is entitled to proceed.

2. A game apparatus including a plurality of bases forming stations and a barrier having a plurality of openings of different values and through which a missile is to be projected to determine the number of bases a player is entitled to proceed, said barrier comprising a pair of plates hingedly connected together and a sheet of fragile material interposed between said plates. 65 70

3. A game apparatus including a plurality of bases forming stations and a barrier having a plurality of openings of different values and through which a missile is projected to determine the number of bases a player is entitled to proceed, said barriers comprising two plates hingedly connected together and a sheet of fragile material interposed between said plates and having characters of value displayed through the 75 80 openings in the plates.

4. A game comprising a playing field a plurality of bases designating stations and arranged in rectangular form, a barrier centrally disposed with respect to the longitudinal dimension of said playing field, and a bouncing plot interposed with respect to said barrier and each end of said playing field. 85 90

5. A game comprising a playing field, a plurality of bases designating stations, and arranged in rectangular form about said playing field, a barrier centrally disposed with respect to the longitudinal dimension of said playing field, and a bouncing plot interposed with respect to said barrier and each end of said playing field, said bouncing plots being of square form and equidistantly 95 100 spaced from said barrier on opposite sides thereof.

6. In a game apparatus, a barrier comprising a vertically disposed panel having openings therein and a pair of standards for supporting said barrier, each of said standards comprising a pair of pivotally connected members and a vertical supporting member carried thereby, said vertical supporting member being connected to the pivotally connected members at their pivoted point. 105 110

7. In a game apparatus, a barrier comprising a vertically disposed panel having openings therein and a pair of standards for supporting said barrier, each of said standards comprising a pair of pivotally connected members and a vertical supporting member carried thereby, said vertical supporting member being connected to the pivotally connected members at their pivotal point, and a plurality of studs carried by said vertical supporting members and adapted for engagement with key-slots in the barrier to support the latter. 115 120

JEREMIAH J. LYNCH.
